DESIGN FOR A BOTTLE

William G. Zetzmann, New Orleans, La., assignor to Dr. Pepper Bottling Company, Inc., New Orleans, La., a corporation of Louisiana

Application February 21, 1936, Serial No. 61,295

Term of patent 7 years

To all whom it may concern:

Be it known that I, William G. Zetzmann, a citizen of the United States, residing at New Orleans, in the parish of Orleans and State of Louisiana, have invented a new, original, and ornamental Design for Bottles, of which the following is a specification, reference being had to the accompanying drawing, forming part thereof.

I claim:

The ornamental design for a bottle substantially as shown.

WILLIAM GEO. ZETZMANN.
